United States Patent Office

Des. 190,670
Patented June 20, 1961

190,670

LINK FOR AN EXPANSIBLE BRACELET OR SIMILAR ARTICLE

Nathan Goodman, Forest Hills, N.Y., assignor to Baldwin Bracelet Corporation, New York, N.Y., a corporation of New York

Filed Jan. 11, 1961, Ser. No. 63,540

Term of patent 7 years

(Cl. D45—4)

Fig. 1.

Fig. 2.

Fig. 3.

Fig. 4.

FIGS. 1 and 2 are respectively a top plan view and a side elevational view of a link for an expansible bracelet, showing my new design;

FIG. 3 is a sectional view taken on line 3—3 of FIG. 1; and

FIG. 4 is a perspective view of the link.

I claim:

The ornamental design for a link for an expansible bracelet or similar article, substantially as shown.
